(57) **CLAIM**

The ornamental design for an electronic reader module of an electronic latch assembly, as shown and described.

DESCRIPTION

FIG. 1 is a perspective view of an electronic reader module of an electronic latch assembly;

FIG. 2 is a front view of the electronic reader module illustrated in FIG. 1;

FIG. 3 is a rear view of the electronic reader module illustrated in FIG. 1;

FIG. 4 is a side view of the electronic reader module illustrated in FIG. 1, as viewed from the left side of FIG. 9;

FIG. 5 is a side view of the electronic reader module illustrated in FIG. 1, as viewed from the right side of FIG. 9;

FIG. 6 is a top plan view of the electronic reader module illustrated in FIG. 1; and

FIG. 7 is a bottom plan view of the electronic reader module illustrated in FIG. 1.

FIG. 8 is a perspective view of another electronic reader module of an electronic latch assembly;

FIG. 9 is a front view of the electronic reader module illustrated in FIG. 8;

FIG. 10 is a rear view of the electronic reader module illustrated in FIG. 8;

FIG. 11 is a side view of the electronic reader module illustrated in FIG. 8, as viewed from the left side of FIG. 9;

FIG. 12 is a side view of the electronic reader module illustrated in FIG. 8, as viewed from the right side of FIG. 9;

FIG. 13 is a top plan view of the electronic reader module illustrated in FIG. 8; and,

FIG. 14 is a bottom plan view of the electronic reader module illustrated in FIG. 8.

The broken lines depict portions of the article that form no part of the claimed design.

(Continued)

The diagonal cross-hatching on the lower section of the article depicts a light element that is part of the claimed design.

1 Claim, 14 Drawing Sheets
